(57) **CLAIM**

The ornamental design for a pendant, as shown and described.

DESCRIPTION

FIG. 1 is a top, front perspective view of the pendant of the present invention showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and,

FIG. 7 is a left-side elevational view thereof.

The broken lines depict portions of the pendant that form no part of the claimed design. The surfaces that are unshaded and occur below the broken lines on the front and rear of the pendant form no part of the claimed design.
